ELECTRIC CONTROL MEANS

Henri Feinte, Laval, France

Application February 7, 1952, Serial No. 270,488

1 Claim. (Cl. 323—80)

My present invention is in part a continuation of my copending specification Ser. No. 87,712, filed on April 15, 1949, now abandoned. It has for its object a control system for the selective operation of one or a small number of electrical apparatuses out of a plurality of apparatuses, said system resorting to the well-known connections including a series of resistances in parallel associated each with a stationary contact-piece while a sliding elongated contact-piece is adapted to provide progressively the energization of the stationary contact-pieces starting from one end of the line of said stationary contact-pieces over a supply of current so as to short-circuit an increasing number of resistances, the sliding elongated contact-piece being constituted for instance by a mass of mercury adapted to extend over a variable number of stationary contact-pieces starting from one end of the series of such contact-pieces.

Now, according to my invention, I obtain, through the novel association of L-type networks with a system of the type referred to and including switches adapted to close corresponding short-circuits in succession through the progression of any movable member, such as a column of mercury in a tube or of a train along its rails, the selective operation of relays or the like apparatuses inserted in the series arms of the successive L networks. Such networks are well-known and their properties are resorted to in order to provide for a reduction underneath a predetermined threshold of the current feeding them, except one or a few networks fed by the last switch or switches that are being engaged by the movable member. The formulae of calculation of such networks allow selecting the value of the different impedances, whether those arranged in parallel or those arranged in series, or at the end of the line of networks, i. e. the so-called iterative impedances, in a manner such that it is possible to obtain predetermined drops in voltage that gradually decrease from one energized series impedance to the next, the short-circuited impedances having obviously no action on the relays or apparatuses to be controlled.

My present invention resorts to the modifications in the characteristic values of the currents flowing through successive series impedances of a chain of such L type networks when the chain is fed through a varying number of its apices, each apex being constituted by the connection point between two successive series impedances and the associated parallel impedance.

In order to obtain the desired selective operation, I resort to electric relays or apparatuses that are adapted to become operative as soon as the intensity flowing through them rises above a predetermined minimum value or threshold. When no current passes through them or when the intensity of current flowing through them is smaller than this threshold, the apparatus remains or becomes inoperative. Apparatuses of this kind are constituted by relays adapted to be energized only for a predetermined number of ampere-turns, incandescent bulbs that are illuminated only for a drop in voltage

2

above a predetermined value and, generally speaking, all devices used for signalling or relaying purposes and operating above a predetermined intensity of current.

My invention covers a method and means for the selective operation of one or more of a plurality of apparatuses provided with such a threshold operation, which apparatuses are inserted in the series arms of the chain, fed through one or more of its apices, the distribution of which is selected in accordance with the type of apparatuses to be considered while the values of the impedances of the chain are selected in a manner such that the currents passing through the different series impedances rise above the thresholds of the corresponding apparatuses only in a predetermined number of networks or cells lying to one side of the last apex or apices that are fed, according to the number of apparatuses to be simultaneously operated through such an apex or apices.

The execution of my invention is thus provided chiefly by a chain of impedances constituted by a number of L cells wherein the series impedances are constituted at least partly by the apparatuses that are to be operated selectively while the free ends of the parallel impedances are connected on one hand with one terminal of a common supply of current and on the other hand with one of a succession of stationary contact-pieces that are thus electrically connected with the apices of the chain, for cooperation with a slidingly movable contact-piece connected with the other terminal of said supply and engaging a variable number of stationary contact-pieces. The sliding contact-piece may thus cooperate with all the stationary contact-pieces between one end of the chain and a predetermined selected contact-piece, or else with a group of successive contact-pieces, or again with one, two or more contact-pieces, in which latter case the contact-pieces cooperating with the sliding contact-piece are separated from one another by a constant or variable number of intermediary contact-pieces.

The values of the impedances of the chain are chosen in a manner such as to allow the selective high energization of one or more of the apparatuses inserted in one or more of the series arms of the L networks, said apparatuses being each directly connected with an apex corresponding with a contact-piece engaged by the sliding contact so as to be fed with a higher electric energy when the apex corresponding to the apparatus considered is about to be reached or is the last to be reached by the moving sliding-contact-piece. When a permanently closed circuit is used, it is possible to make the drop in potential between the terminals of a series impedance provide for control without it being necessary to take into account the fact that the last contact-piece cooperating with the sliding contact-piece corresponds with one end of the series impedance or with the other end.

It is also possible to cut out the presence of any controlled apparatus from a certain number of series impedances and again it is possible to insert further apparatuses in the parallel impedances of the chain, for instance when it is desired for an apparatus to become operative as soon and as long as the sliding contact engages a contact-piece corresponding to the apex to be considered.

I have illustrated in accompanying drawings various wiring diagrams corresponding to various embodiments of the invention.

65 In said drawings:

Fig. 1 is a wiring diagram of a known arrangement for the successive operation of a number of apparatuses through the movement of a sliding contact-piece.

70 Fig. 2 is a wiring diagram of an arrangement executed in accordance with the invention and adapted to show the frequency of the modification in level of a mercury col-

umn, said arrangement illustrating the principle of my invention for the selective operation of the different apparatuses.

Fig. 3 is a wiring diagram of a system controlling the filling of a container with a conductive liquid in accordance with the present invention.

Fig. 4 is a modification of the arrangement according to Fig. 3, a further apparatus being inserted in a parallel impedance.

Fig. 5 is a wiring diagram of a control system indicating the extent of filling of a boiler, as provided in accordance with the invention.

Fig. 6 is a modified diagram of a control device indicating the degree of filling of a boiler with the simultaneous operation of two apparatuses.

Fig. 7 is a wiring diagram provided in accordance with the invention for the control of the signalling means on a railway line.

Turning to Figs. 1 and 2, the arrangements illustrated provide for the operation of meters recording the modifications in the level of a mercury column 1 inside a tube 2 respectively, in accordance with known art and with the present invention.

In accordance with the previously known arrangements as illustrated in Fig. 1, the tube 2 filled with a mass of mercury 1 contains a number of contact-pieces 3 at different levels inside said tube. Each of said contact-pieces is connected with one of the terminals of an electromagnetic meter illustrated in the present case by a winding 4. The second terminal of each meter is connected through a return wire 5 with one of the terminals of a supply of energy 6, the other terminal of which is connected with a contact-piece 7 in permanent electric contacting relationship with the mercury column, a protective switch operating periodically and illustrated diagrammatically at 8 being inserted between the supply 6 and the contact-piece 7. This arrangement provides for the operation, each time the switch 9 closes, of all the meters 4 simultaneously, the contact-pieces 3 associated with which are bathed by the mercury column at the time considered, whereby each of said meters receives an impulse.

If it is supposed the switch 8 closes once per second, it is sufficient, in order to ascertain how long the level of the mercury column has remained between two successive stages corresponding to two successive contact-pieces, to deduct from the value indicated by the meter connected with the lower contact-piece the value indicated by the meter connected with the upper contact-piece considered.

The problem to be solved in the case considered consists in designing the arrangement in a manner such that each meter may indicate the number of seconds during which the level of the liquid reaches a predetermined position i. e. during which it lies between two successive superposed contact-pieces.

The prior arrangement as illustrated in Fig. 1 shows also a drawback from a mechanical standpoint by reason of the fact that the meter corresponding to the lowermost level operates permanently and is thereby submitted to a heavy duty. This leads to the risk of errors without it being possible to ascertain the magnitude of such errors because it is impossible to determine whether all the meters have actually worked uninterruptedly during the period of recording.

Now, my improved arrangement as illustrated in Fig. 2 includes also a number of contact-pieces 10a, 10b, 10c, etc., that are distributed throughout the height of the tube 1 in the same manner as the contact-pieces 3 in Fig. 1. Similarly, a predetermined number of impulse meters 11a, 11b, 11c, etc., are provided, but in contradistinction with the prior arrangement of Fig. 1 they are inserted between the ends of the parallel impedances 12a, 12b, 12c, the free ends of which are connected with one terminal of a source of electrical energy 14.

In a preferred embodiment, the meters may assume a resistance of 500 ohms and they may operate when fed by

a current of 40 milliamperes passing through them while they return to inoperativeness when the current drops down to 28 milliamperes.

As disclosed, these meters are inserted in the series arms 5 of the successive L type networks of the chain, which networks include also the parallel impedances 12a, 12b, 12c, etc. The apices of this chain of impedances are connected with the corresponding contact-pieces, 10a, 10b, 10c, etc. The parallel impedances 12a, 12b, 12c have e. g. a resistance of 500 ohms, while the impedance 13 forming the iterative impedance at the end of the chain has a resistance of 309 ohms. These values are ascertained through the well-known formulas governing such L type networks. The second terminal of the supply of energy 14 15 is connected again through a contact-piece 15 with the foot of the mercury column with the insertion, between said contact-piece 15 and last mentioned terminal, of a periodically operating switch illustrated diagrammatically at 16. The source of energy 14 is chosen so as to produce 20 a permanent voltage of 36 volts.

It is apparent that any of the meters 11, having its terminals connected with two contact-pieces that are both in contact with the mercury column, is short-circuited and produces no impulse when the periodically operating 25 switch 16 closes. The meter 11d of Fig. 2 for which only the lower corresponding contact-piece 10d is in contact with the mercury column while the next highest contact-piece 10e is free from such a contact, is fed in the case considered with the comparatively large current while the 30 meter 11e and the following meters that lie higher than the meter 11e are fed with currents, the intensities of which decrease for meters at increasingly high locations. It is therefore apparent that when the contact-piece 16 is 35 closed, only the meter 11d is fed with current of an intensity that is sufficient for it to be operative while the higher meters 11e and 11f remain inoperative by reason of the passage of weak currents that are underneath the threshold intensity of 28 milliamperes.

It should be remarked that it is possible to check whether the meters are operating reliably because the total 40 number of impulses recorded should be equal to the number of times the periodically operated switch 16 closes, each closing of last mentioned switch providing for one impulse and only one, said impulse being provided by the 45 meter inserted in the impedance that at the moment considered is inserted between two contact-pieces 10 of which one is bathed and the other is not bathed by the mercury column.

In the further embodiment illustrated by way of example in Fig. 3, the general wiring diagram is similar in its 50 principle to that illustrated in Fig. 2 and is adapted for controlling a pump feeding a container 17, which latter is to be filled with water or the like conductive liquid. The conductive wall of the container carries two contact-pieces 19 and 20 that are carried in insulating sleeves. The contact-piece 19 is located in register with the minimum level of the liquid, beneath which the liquid level should not sink. The contact-piece 20 registers with the maximum level beyond which the liquid should not rise. The L networks includes series arms constituted by a relay 21 which is inserted in series between an illuminating bulb 22 and its associated impedance 23 on one hand and a second incandescent bulb 25 and its associated impedance 25, on the other hand. The chain is completed through the parallel impedances 26a, 26b, and the terminal iterative impedance 27.

The apex of the chain that corresponds to the impedance 26a is connected with the contact-piece 19 and the apex corresponding to the impedance 26b is connected with the contact-piece 20. The free ends of the impedances 26a, 26b and 27 are connected with one terminal of the supply of energy 28, the other end of which is grounded through the body of the container at the point 29 forming part of a first network and connected with the 70 75 end of the series impedance constituted by the incandes-

cent bulb 24 and the associated impedance 25. The relay 21 provides for the energization of a motor 30 controlling the pump. The operation of the wiring diagram illustrated is the same as in the case of Fig. 2; it is timed with reference to the operation of the relay 21 in a manner such that said relay closes a switch in the circuit of the motor 30 when the level of liquid lies between the contact pieces 19 and 20 so that said relay may receive a sufficiently high intensity for it to operate. As soon as the contact-piece 20 is bathed by the liquid, the relay 21 is short-circuited, the corresponding switch opens and de-energizes the motor 30.

The values of the auxiliary impedances 23 and 25 are calculated in a manner such that the total impedance of each incandescent bulb 22 or 24 together with that of the associated impedance 23 or 25 is equal to the impedance of the relay 21 and it is also such that the drop in voltage inside the bulb 22 is not sufficient for illuminating said bulb when the connection is provided through the contact-piece alone. As soon in fact as the liquid level lies between the contact-pieces 19 and 20 and the motor 30 is energized, the intensity of the current passing through the bulb 22 and the associated impedance 23 is not sufficient for said bulb to be illuminated; in contradistinction, when the liquid level reaches the contact-piece 20, the relay 21 is short-circuited and opens so that the bulb 22 receives a sufficient electrical energy and is illuminated to show the highest allowed liquid level is reached. If, on the other hand, the liquid level drops underneath the contact-piece 19 by reason of any faulty operation, for instance if the pump sucks no liquid any more or if substantial leakages appear in the container, the bulb 24 is illuminated so as to show an abnormal liquid level and an abnormal operation have been reached; at the same time, the relay 21 that is fed with current of an intensity that is less than the operative value opens so that the motor is no longer operative. From this moment onwards, the whole arrangement is completely stopped and can be started again only through manual interference. This cuts out any abnormal operation such as that wherein the pump rotates without sucking any liquid.

Fig. 4 shows the same wiring diagram and the same references as in Fig. 3 with the difference that the parallel impedance 26 is constituted by a relay 31 which is inserted exactly in the same manner as the meters 4 in the case of Fig. 1, i. e. in accordance with the prior arrangements, the operation being exactly the same when current is passing through the contact-piece 19. This arrangement may serve for controlling the opening of slide valves whenever the level of liquid rises above the minimum level. The slide valves being thus open close when for any reason whatever, the level of liquid drops underneath said minimum level.

The arrangement illustrated in Fig. 5 shows the wiring diagram of a control system for the feeding of a boiler.

The water chamber in the boiler is shown diagrammatically at 32. In the walls of said water chamber are provided insulated contact-pieces 33, 34, 35, 36, 37 and 38. This arrangement provides in direct relationship with the location of the varying water level in the chamber the execution of the following steps:

(a) The operation of an acoustic alarm and the opening of a release of exhaust slide valve when the water level rises beyond a predetermined maximum location.

(b) The illumination of a signal while the water level is normal.

(c) The starting of a pump having a small capacity for equilibrating the losses when the boiler lies under pressure without any steam being used.

(d) The starting of a medium capacity pump which should be operated in the case of normal utilization of the steam.

(e) The starting of a pump of large capacity in order to make up for a large consumption of steam.

(f) The operation of an acoustic alarm device simul-

taneously with the closing of the slide valve controlling the feeding of the boiler when, for any reason whatever, the water level drops underneath the minimum safety level.

5 The contact-pieces 33 to 38 are distributed throughout the height of the boiler and are located at different levels corresponding to the control of the different operations. The chain includes a relay 39 providing for the control of the operation of the acoustic alarm device and for the closing of the fuel slide valve, a relay 40 controlling the operation of the motor driving the pump of large capacity, a relay 41 controlling the motor driving the pump of medium capacity, a relay 42 controlling the motor driving the pump of small capacity, an incandescent bulb 43 mounted in series with an associated impedance 44, which incandescent bulb is operative as an indicator when the water level is normal and a relay 45 controlling the acoustic alarm device and the exhaust-controlling slide valve.

20 The L networks are completed by the parallel impedances 46a, 46b, 46c, 46d, 46e and by the iterative impedance 47. The free ends of the parallel impedances and of the iterative impedance are connected through a return wire 48 with one terminal of a source of energy 49, the other terminal of which is grounded through 25 the wall of the water chamber 32. The values of the impedances 46 and of the impedance 47 are calculated in accordance with the usual formulae of L networks, taking into account the impedances of the relays and of the signalling means such as 45 and also the maximum 30 and minimum intensities that are required for starting the relays and for closing them in a manner such that when the circuit is closed between the liquid in the water chamber 32 and one or more of the contact-pieces 33 to 38, only the first relay beyond the contact-piece immediately below the water level receives sufficient current for ensuring its operation.

25 Consequently, it is necessary to provide, in accordance with the location of the water level in the chamber of the container 32, a closing of the circuit between the body of 40 the grounded container 32 and the different contact-pieces 33 to 38 including all those contact-pieces that are bathed by the liquid and no other.

30 By reason of this insertion of the relays in the chain, the apices of which are connected with different contact-pieces, only the relay or the signalling means lying between the last contact-piece bathed by the liquid and the first contact-piece that is not bathed receives a current of sufficient intensity for it to become operative.

35 Supposing the water level lies above the uppermost contact-piece 38, the relay 45 alone is energized and the corresponding acoustic alarm device becomes operative and warns of the arrangement operating in some faulty manner; at the same time, the exhaust slide valve opens and produces consequently a lowering of the water level until said exhaust slide valve closes again upon the water level dropping underneath the contact-piece 38. At this moment, the incandescent bulb 48 is fed in its turn with a sufficiently high current and becomes illuminated, which indicates the water level is normal. When however the water level sinks by reason of losses of fluid underneath the next contact-piece 37, the signalling bulb 43 that receives no more current of sufficient intensity is extinguished and the relay 42 forming the next series impedance closes and produces operation of the pump of 40 low capacity. If further and larger losses of water are produced through a large consumption of steam or the like reasons and the water level sinks further so that the contact-piece 36 is no longer bathed by the liquid, the relay 41 closes and starts the pump of medium capacity into operation. Normally, such a pump of medium capacity is sufficient for ensuring a normal feed of water into the boiler. If, for any reason whatever, the consumption of water rises above normal, the water level drops underneath the next contact-piece 35. At this 45 moment, the relay 40 closes while the deenergized relay

41 opens and this produces the operation of the pump of large capacity while the pump of medium capacity stops operation. Upon still further dropping of the water level, as a consequence of some leakage or by reason of a failure of the pump, said level sinking then underneath the contact-piece 34, the next relay 39 closes, the acoustic alarm device is started and the fuel slide valve closes. From this moment onwards the whole arrangement is at a standstill and can be started again only by hand. This prevents cold water from entering a superheated boiler which might lead to serious damage.

In the modification illustrated in Fig. 6, the water chamber is again shown at 32 while the contact-pieces 50 are provided in a manner similar to the contact-pieces 33 to 38 of Fig. 5. In this embodiment, the following operations may be obtained in succession.

(a) The operation of an acoustic signal and the opening of an exhaust slide valve whenever the water level rises above a maximum level;

(b) The operation of a signal when the upper limit of normal water level is reached;

(c) The simultaneous operation of two signals corresponding to the upper and lower limits allowed for the water level, in case the water level actually lies between two predetermined limits;

(d) The operation of the signal corresponding to the lower limit of the water level, together with the starting of a pump of small capacity when the water level in the chamber 32 is sufficient but sinks as a consequence of losses underneath an intermediary level between the extreme levels allowed;

(e) The operation of a pump of small capacity and of a pump of medium capacity when, as a consequence of the consumption of water, the water level sinks under its normal lower limit;

(f) The operation of two pumps of medium capacity when, for any reason whatever, the water level sinks too much;

(g) The operation of a signal indicating a lack of water together with the closing of the fuel slide valve whenever the water level sinks underneath a critical value, whereby a reduction in the production of steam provides again a return to normal level.

(h) Lastly, in case the operation of the medium capacity pump is not sufficient for maintaining the water level while the production of steam is completely cut-out and if the water level continues sinking as a consequence of a leakage, all the water feeding means are closed while the signal corresponding to a lack of water continues operating and the fuel slide valve is closed and the whole arrangement comes simultaneously to a standstill.

In the case of the abovementioned stages of operation, it is to be remarked that, in the majority of cases, two groups of apparatuses operates simultaneously, each group being connected so as to operate selectively with the preceding apparatus or with the following apparatus.

In order to achieve this result, the successive series impedances are constituted by the relays 51, the incandescent bulbs 52 associated in series each with an auxiliary impedance 53 and inoperative impedances 54 while the parallel impedances 55 connected with the connecting points provided between the successive series impedances form with the latter the desired L networks. The chain of L networks is fed by a supply of energy 56 the terminals of which are connected respectively with the free ends of the impedances 55 and with the grounded mass of the container 32.

In order to provide the desired succession of the above-listed steps of operation, the chain of L type networks includes in series an inoperative impedance 54 inserted between the second terminal of the supply 56 and the connecting point or apex of the L network that is connected with the lowermost contact-piece 50, a first relay 51 controlling the signal corresponding to lack of water and to the closing of the slide valve, a second

relay 51 controlling the motor driving the pump of medium capacity, a third relay 51 providing for the operation of a second pump of medium capacity, a fourth relay 51 controlling the motor driving the pump of small capacity, an incandescent bulb 52 forming the signal corresponding to the lower limit allowed for the normal water level, a second incandescent bulb 52 providing a signal corresponding to the upper limit of normal water level, an inoperative impedance 54 and a last relay 51 forming a signal corresponding to a water level that is too high and to the operation of the exhaust slide valve. Taking into account the fact that the values worked out for the impedances are such that, as soon as a contact-piece 50 is bathed by the liquid and the following contact-piece lies above the water level, the two impedances extending in series above the apex connected with the first mentioned liquid-bathed contact-piece, are the only ones to be fed with a current of sufficient intensity either for energizing the relays corresponding thereto or else for illuminating the incandescent bulb inserted in the corresponding member of the chain, it is consequently obvious that the above-defined conditions of operation are satisfied.

Figs. 7 shows two railroad rails 60—61 forming a track over which one, two or more trains are moving. The sliding contact-piece is constituted by the actual train running over the track. It is supposed that the train runs only in one direction, which direction is in the example considered that from the right hand side to the left hand side of Fig. 7. The rail 61 is adapted throughout its length to be energized through connection with one terminal of a source of energy, in the case illustrated the positive terminal. The rail considered from right to left includes a succession of sections 61a, 61b, 61c, 61d, the lengths of which are defined in accordance with the requirements of traffic. The single sections are insulated electrically with reference to one another and the rails in each section are electrically interconnected so that each section may be energized throughout its length. Each end of a section is connected with the end of the next section through a polarised relay 62. The relays 62 are all similar to one another and are designated by the reference numbers 62a, 62b, 62c etc., and they assume for instance a resistance of 200 ohms each. Their threshold of operation lies in the vicinity of 80 milliamperes and it is ascertained that with a sufficient safety margin, their operation is perfectly reliable for 95 milliamperes while their inoperativeness is also reliably obtained for 65 milliamperes. They are adapted to provide for the passage of a current of 250 milliamperes without any substantial heat being evolved. Such relays are stable and are easy to execute. Each of these relays is associated with a signal through an arrangement providing for the signals, operating with the conventional red and green lights, to remain red while the green light is extinguished or dimmed whenever the relay is inoperative. When the relay is actuated and the contact-piece thereon is shifted towards the right hand side of Fig. 7, the red light is extinguished or dimmed in its turn while the green light is illuminated or returned to normal intensity which shows that the track is free. The contact-piece on the left hand side of Fig. 7 is not used in the arrangement considered.

It has been believed unnecessary to overload the drawing and description with the control means for the signal, still less with the actual signal. The latter needs not be located exactly at the point at which two sections meet and it can stand at a predetermined distance thereof in conformity with the requirements of traffic. It may also be connected with other signals such for instance as signals for half-track or stop signals.

Alongside of the track, there extends a wire 63 connected with the positive terminal of the supply of current 64 producing a 50-volt current. Each section of the rail 61 is separately connected with the wire 63 through a resistance 64 of 300 ohms. These resistances are des-

gnated individually by the reference numbers 64a, 64b, 64c, 64d, etc., and form with the impedances of the relays 61 a chain of networks.

It may be assumed that the resistance of the lateral wire 63 and also that of the track rails may be neglected. If, however, this is not the case, it is possible to make up for this by inserting a plurality of auxiliary supplies of current in parallel with the first mentioned supply at different points of the track or else these further resistances are taken into account in the calculation of the wiring diagram.

In the case of the example considered, it is necessary that the iterative or terminal resistance 65 of the network should assume a value of 65 ohms.

1st case.—Supposing there is no train running over the track, all the relays are inoperative and all the signals are closed.

2nd case.—There is a single train on the track; said train running for instance entirely over the section 61c, we will consider the front thereof two L-networks and the same number to the rear of the train. The relay 62b behind the train is fed with a current of 137 milliamperes in a direction such as will urge the movable contact-piece against the stationary contact-piece to the left thereof. The signal remains thus closed. The relay 62a is fed with only 62 milliamperes and remains inoperative so that the corresponding signal also remains closed. As the train continues its travel over the section 61c, the relay 62c is fed with 137 milliamperes in a direction such as will urge the corresponding contact-piece to the right, which opens the signal controlled by said relay. The relay 62d, in contradistinction, is fed only with 62 milliamperes and remains inoperative so that the corresponding signal remains closed. As readily apparent, the conditions of operation for 62e and the subsequent relays are similar.

The signal corresponding to the relay 62c is now open and the train may enter the section 61d. When its forward end enters the next section 61d while its rear end is still on the section 61c, the relay 62c is short-circuited and becomes inoperative so that the corresponding signal closes behind the driver. At the same time, the relay 62d opens its signal and permits the entrance of the train into the section 61e. When the last axle of the train has entered the section 61d, the contact-piece of the relay 62c is energized in a direction opposed to its prior energization so that its contact-piece is urged towards the left and the corresponding signal remains closed.

Thus if only one train is running over the track, all the signals in front of it are closed except one. When the train progresses from one section to the next, it provides for the opening of a single signal in front of it and it may thus travel through the entire track without stopping.

I will now disclose the operation of the signal when the track is occupied by a second train.

3rd case.—There are two trains on the track considered. Having elucidated the problem of the presence of two trains on the same track, this solves immediately the problem of operation for any number of trains simultaneously occupying the track.

A train having entered the section 61d and assuming in accordance with a hypothetical supposition, that there is another train ahead of it in the section 61e, the relay 62d is short-circuited and is therefore inoperative and provides for the closing of the corresponding signal. This closes the entrance into the section 61e and protects the train in last-mentioned section. It may be objected that the last axle of one train has perhaps already entered the section 61e when the first axle of the next train has entered the section 61d, which would unavoidably lead to a collision. However, this objection does not hold, in the first place because, as already disclosed hereinabove, the signal is not necessarily located located at the meeting point between two sections and moreover because no

train is so to speak set over a section and the arrangement defined provides the necessary safety with a completely free intermediary section as will appear from the following disclosure:

5 In actual practice, the train lying in the section 61d cannot move any further while the track in front of the train in the section 61e is free and last-mentioned train may enter the next section 61f. When the first axle of the train has entered said section 61f, the relay 62e is short-circuited and becomes inoperative so that the corresponding signal closes. The train that is in section 61d has therefore in front of it two closed signals as the relays 62d and 62e are both short-circuited and consequently inoperative, and therefore said first train is constrained 10 to remain in the section 61d.

When the last axle of the running train enters the section 61f, the relay 62e will remain inoperative as it is fed with only 62.5 milliamperes and the corresponding signal remains closed. At the same time, the relay 62e is also 15 fed with 62.5 milliamperes and the corresponding signal remains closed. The train held fast in the section 61d cannot continue running as there are two closed signals in front of it.

When the train in the section 61f continues moving, 20 this produces a novel position for the relays and the signals which I will now examine. When the front axle enters the section 61g, the relay 62f becomes inoperative and the corresponding signal closes. Furthermore, there is no modification in the relays 62e or 62d nor in the 25 signals associated therewith. The running train is thus protected by three closed signals. When the last carriage of the running train enters the said track section 61g, the relay 62f is fed with 100 milliamperes and shifts its contact-piece towards the left so as to keep the corresponding signal closed. The relay 62e receives no current and remains closed. The relay 62d is fed with 100 30 milliamperes in the operative direction so that its contact-piece is shifted towards the right so as to re-open the track for the train lying in the section 61d. This latter train may therefore enter the section 61e.

As concerns this latter case, it is possible to show that when the number of sections and of relays between the trains increases:

1. The relays lying between two trains are fed with 40 current of constant direction and the intensity of which ranges between 100 and 137 milliamperes, which latter value is reached only when the track is completely free and for such a range of intensities the corresponding signals open in front of any train and close when it has 45 passed.

2. The current in the relays preceding and following the relays considered increases from 0 to 62 milliamperes which latter value is only reached when the train is very far away, the corresponding signals being closed for such 50 intensities flowing through the relays.

3. The current passing through the relays other than those considered hitherto is still weaker so that said relays are all inoperative and the corresponding signals are closed.

60 It is possible to develop these facts in a similar manner for any number of trains on the track and there is found that this leads to a system wherein:

1. In the absence of any train on the track, all the signals are permanently closed.

65 2. The trains control the opening of the track, said opening being provided automatically and only for one signal at a time as soon as the track is free. If, on the contrary, the track is occupied, the train is automatically stopped.

70 3. All the trains are protected by at least two signals while the protected minimum distance between the rear of one train and the front of the next train corresponds to an entire section increased by the difference between the controlling point and the actual signal. The maximum distance that is protected includes two sections

11

plus the distance between the point of abutment between two sections and the actual location of the signal controlled through the relay connected across said point of abutment.

4. Safety is also obtained where there is no current flowing through the relays or when an unexpected breaking appears at any point of the connections. The only possible causes of a disturbance as far as safety is concerned are constituted by an abnormal increase in the voltage of the supply or else by a short-circuit affecting the resistances 64. It is sufficient to resort to very simple protective steps in order to remove these two objectionable possibilities.

In the first place, for instance, it is possible to use as a supply a storage battery or a system of dry cells. As to the second cause of failure, it is possible to give the resistances 64 a suitable shape and a suitable location, for instance they may be subdivided into a plurality of elements that are at a distance from one another and that are suitably protected.

In the above disclosure, I have not considered how the contact-pieces on the left hand side of the relays of Fig. 7 may be used nor how it is possible to return them into their inoperative position. Now these contact-pieces may serve for the connection of complementary signals, acoustic signals, alarm devices or the like arrangements, for instance arrangements providing a breaking of the current in such or such a section, and they may also serve for any purpose that may be useful.

I may mention as an example that the left hand contact-pieces may serve for controlling further signals and for the protection of trains running in the opposite direction over the track, i. e. from the left to the right of Fig. 7.

It is apparent that the problem of traffic on a single

track or on a double track may be solved in a similar manner. These problems are also similar to the problems of the movement of a plurality of lifts in a common shaft.

5 What I claim is:

In an electrical control means comprising a plurality of electrical apparatus, selected from a group consisting of relays, signals, meters, valves and pumps, connected for operation and interruption of operation at least one at a time in sequence depending on the direction of movement of a movable contact means, the said plurality of electrical apparatus being connected in series, a plurality of taps insulated from each other and spaced along the line of movement of said contact means, the said contact means having electrical connection with a terminal of a source of electrical current at one end of said line of movement of said contact means, each of the connecting means between said apparatus having electrical connection with one of said taps for operation in said sequence, each of said connecting means between the apparatus having electrical connections with an impedance, and each impedance having electrical connection with a common lead connected to the other terminal of said source of electrical current.
